ASSIGNORS, BY MESNE ASSIGNMENTS, TO CHARLES J. FOX, OF PHILADELPHIA,
PENNSYLVANIA.

METHOD OF AND APPARATUS FOR INDICATING VACUUM-FEED-SYSTEM CONDITIONS.

Application filed May 13, 1921. Serial No. 469,171.

To all whom it may concern:

Be it known that we, FRANK F. SORENSEN and PEARL C. DYER, citizens of the United States, residing at the city of Philadelphia, county of Philadelphia, and State of Pennsylvania, have jointly invented a certain new and useful Method of and Apparatus for Indicating Vacuum-Feed-System Conditions, of which the following is a specification.

This invention, generally stated, relates to vacuum feed systems for motor-vehicles, motor-boats, and aero-craft and has more especial relation to a method of indicating the gas feed conditions in such systems.

As is well known the feeding of gas to a carburetor by means of a vacuum instead of by means of pressure or gravity is now commonly practised. Contrary to general belief however a feed system of this character needs constant supervision. While various causes as wear, vibration, careless and unskilled attention serve to materially affect the operation of a vacuum feed system, leaks, stoppages and flooding may be probably cited as causing most of the trouble experienced. Leaks occurring in any part of the system, as in the gas line, may cause loss of gas, difficulty in starting of the engine, irregularity in running and frequently failure of the system to function. Stoppages may occur in any part of the gas line and as they seldom develop suddenly the operator is usually advised of the fact when his motor ceases to operate. Flooding of the vacuum chamber of the system, if allowed to continue, may cause what is termed "burning out" of the engine. This occurs because gas, drawn into the manifold through the suction line, washes oil from pistons and rings, finds its way to the crank case, and mixing with the oil in the crank case, destroys the lubricating value of the oil. Even when these leaks, stoppages and floodings occur it is often very difficult to locate the trouble and repair men frequently spend many hours endeavoring to locate the exact trouble.

It is the leading object of the present invention to provide means whereby the above described defects when occurring in a vacuum feed system may be instantly detected

by the operator of a motor-vehicle, motor-boat or aero-craft by incorporating in such system a detector or indicator which is responsive to the slightest variation of gas feed conditions. Other and further objects relate to the provision of general arrangement, connection and combination of parts in a vacuum feed system for attaining the results sought by the said leading object.

The invention consists of the improvements hereinafter described and finally claimed.

The nature, characteristic features and scope of the invention will be more fully understood from the following description taken in connection with the accompanying drawings forming part hereof, and in which:

Fig. 1, is a more or less diagrammatic view of the conventional vacuum feed system having incorporated therein indicating means embodying features of the invention.

Fig. 2, is a view in central section of the indicating means shown in Fig. 1, about to be assembled.

Fig. 3, is a similar view showing said parts assembled.

Fig. 4, is a face view of Fig. 3.

Fig. 5, is a similar view with the glass front removed, and

Figs. 6 and 7 are front and sectional side views respectively of a somewhat modified form of indicator shutter.

For the purpose of illustrating our invention, we have shown in the accompanying drawings one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of the instrumentalities as herein shown and described.

In the drawings, 10 designates an internal combustion engine, 11 a carburetor connected to the engine manifold, 12 a vacuum chamber connected upon one side of its float by means of a suction line 13 with engine 10 and connected upon the other side of its float, by means of a gas feed line 14 with

the carburetor 11. Upon the same side of the float as the suction line 13, said chamber 12 is connected by line 15 with a gas tank 16. The above described parts are of 5 conventional form and as arranged comprise a well known vacuum feed system. Our method of indicating gas feed conditions in such a system consists in introducing to the system visual indicating means operable by suction as the engine 10 operates, which means is connected to vacuum chamber 12 upon that side of its float to which is connected suction line 13 and gas line 15. In a motor-vehicle said means is supported 10 by the dash-board in plain view of the operator. In the drawings 17 indicates a dashboard, 18 a casing for enclosing the indicating means and 19 a pipe connecting said casing interior with the vacuum chamber 12. 15 The face of casing 18 is open and has fitted thereto a glass front 20 which for instance may be opaque provided with a transparent portion or window 21. To the rear of such front is positioned a segmental shutter 22, pivoted as at 23 to a fixed disc-like member 24. The shutter is divided by a color line so that in one position before window 21 it may show for instance "white" and in its other position may show for instance 20 "red." Slidable endwise through member 24 is a stud 25 which carries a pin 26 curved at one end as shown at 27 in Fig. 3, and which penetrates an opening 28 in shutter 22 the opening and pin forming a loose fit. 25 Thus as the stud moves endwise shutter 22 is shifted to left or right around its pivot point, the pin 26 functioning as a cam. The stud 25 adjacent its point of penetration of member 24 is provided with a head 29 and 30 between the rear face of said member and said head is a coiled spring 30. Having screw-threaded relation with casing 18 is a cap 31 carrying a diaphragm 32. In the drawings a hollow spherical diaphragm of 35 flexible material as rubber is shown. Communicating with the diaphragm interior is a hollow nipple 33 which is fixed to cap 31 and to which nipple the diaphragm is secured. When the cap 31 is screwed to place 40 as shown in Fig. 3, the diaphragm 32 abuts against and is slightly depressed by head 29. The operation of the above described connection of parts may be described as follows:—With engine 10 stopped the shutter 22 shows "white" before window 21. This is because no vacuum is in the system and diaphragm 32 causes stud 25 to attain its outermost position thus holding shutter 22 fixed. With the engine working gas is 45 drawn from tank 16 into vacuum chamber 12 by means of suction through line 13. Simultaneously such suction draws diaphragm 32 in a direction away from head 29 whereupon stud 25 by reason of spring 30 50 moves backward thus causing shutter 22 to move to the left in Fig. 5 and show "red". When the "spill" or "suck" is completed the diaphragm is free to move to the left in Fig. 3, thus again causing shutter 22 to be moved to show "white" by means of the 55 curved end of pin 26 operating cam-fashion upon said shutter. As long as the system is in proper working order this alternate showing of "white" and "red" before window 21 occurs. With the engine operating and the shutter continuously showing "white" before window 21 however is an indication that an air leak has occurred in the system and that consequently no vacuum exists. Should the shutter continuously show "red" 60 one of two conditions may be present:—

(a) Flooding will have destroyed the efficiency of rubber diaphragm, or fuse, or

(b) stoppage of gas by dirt or other obstruction may be present in the system. 65

Instead of the type of shutter shown in Figs. 2 to 5 we may employ the type of shutter shown in Figs. 6 and 7. Instead of the shutter moving from right to left it is pivoted to move upwardly and downwardly around its pivot point 33. The side walls of the shutter are slotted as at 34 in which slots work a pin 35 carried by stud 25. Otherwise the same construction of parts are employed. 70

Among the advantages claimed for the above described method of observing gas conditions in a vacuum feed system mention may be made of the following:—

No alteration of standard vacuum feed 75 systems is required in incorporating therein our improved method of indicating trouble and defects; the operator has in plain sight at all times a positive indication of both perfect and faulty performance of the system; the added device is simple and cheap to manufacture and may be readily installed in a few moments' time; and if an owner of an automobile, for instance, has not equipped his car with the above described device 80 and consults a repair man about faulty performance of his vacuum feed system, the repair man may test out such faulty system by means of one of the indicators above described. This last mentioned advantage is 85 important since the device thus becomes an adjunct of repair shops for testing purposes as well as efficient for use in vacuum feed systems per se. 90

It will now be apparent that we have 95 devised a novel and useful construction which embodies the features of advantage enumerated as desirable in the statement of the invention and the above description and while we have in the present instance shown 100 and described the preferred embodiment thereof which has been found in practice to give satisfactory and reliable results, it is to be understood that the same is susceptible 105 of modification in various particulars with- 110

out departing from the spirit or scope of the invention or sacrificing any of its advantages.

What we claim is:

- 5 1. In apparatus of the character stated a vacuum feed system including a vacuum chamber and feed lines, a casing provided with a window, a shutter movable before said window, a diaphragm responsive to changes in said vacuum chamber, means connected between said diaphragm and shutter for operating the latter said diaphragm normally holding said shutter in stationary position, and a pipe connected to said chamber upon the same side of its float as said suction line, said pipe leading to said casing to the rear of and communicating with said diaphragm.
- 10 2. An indicating device for vacuum feed systems comprising a casing having a window at one end, a shutter movable before said window, a hollow spherical diaphragm normally containing air, located within said casing, means for exhausting air from said diaphragm, an endwise shiftable member in abutting position with said diaphragm connecting with said shutter for moving the same in one direction upon exhaustion of air from said diaphragm and for moving said shutter in another direction as said diaphragm returns to normal position.
- 15 3. In combination a vacuum chamber, a casing having a window at one end, a shutter movable before said window, a hollow spherical diaphragm within said casing, a
- 20 pipe communicating with said diaphragm connected to said chamber, means abutting against said diaphragm connected with said shutter for moving the same in one direction upon exhaustion of air through said vacuum chamber and for moving the shutter in another direction as said diaphragm re-fills with air.
- 25 4. In combination a vacuum chamber, a casing in communication with said chamber by means of a suction line, a diaphragm within the casing, a signal operably connected with said diaphragm said signal and diaphragm being operable to move in one direction upon exhaustion of air from beyond said diaphragm, and being arranged to move in an opposite direction when said exhaustion of air has been completed.
- 30 5. In combination a vacuum chamber, a casing having a window, a suction line connecting said chamber and casing a signal movable before said window, a diaphragm within the casing, means connected to said signal which means is so arranged with respect to the diaphragm that upon exhaustion of air from beyond said diaphragm said diaphragm and signal move in one direction, said diaphragm and signal being arranged to move in another direction when said exhaustion of air has been completed.

In testimony whereof, we have hereunto signed our names.

FRANK F. SORENSEN.
PEARL C. DYER.
